HARRY F. SMITH, OF DAYTON, OHIO, ASSIGNOR TO THE GAS RESEARCH COMPANY, OF DAYTON, OHIO A CORPORATION OF OHIO

GAS PRODUCTION

Application filed May 16, 1921. Serial No. 469,976.

This invention relates to gas making, and more particularly to the generation of gas from carbonaceous fuel.

One of the principal objects of the invention is to provide apparatus for generating gas from carbonaceous fuel, which is so constructed that generation of the gas is automatically controlled.

Another object of the invention is to provide gas generating apparatus in which generation of the gas is automatically started upon the demand for gas, and automatically stopped when the demand for gas ceases.

Another object of the invention is to provide gas generating apparatus for supplying gas for domestic or home purposes, in which means is provided for controlling the generation of gas to meet home requirements, such means being, preferably, automatic.

Still another object of the invention is to provide a gas generation system of the character referred to which may be easily started, requires little attention during operation, may be safely operated by unskilled attendants, which utilizes cheap and readily available fuels in the generation of gas, and which will produce a gas of sufficient heat value to operate the ordinary domestic appliances, such as cook stove, heating apparatus, gas light, and the like.

Other objects and advantages of the invention will be apparent from the description set out below, when taken in connection with the accompanying drawing.

For purposes of description the invention is illustrated as embodied in a gas generating system particularly adapted for domestic purposes. It is, obviously, just as applicable to the generating of a gas for any desired use.

In the accompanying drawing, in which like characters of reference designate like parts throughout the several views thereof,

Fig. 1 illustrates, somewhat diagrammatically, and in elevation, a gas generating system embodying this invention, certain parts being shown in section to more clearly disclose the details of construction;

Fig. 2 is a view corresponding to Fig. 1 of a somewhat modified system, in which a larg-

er gas storage is provided than is present in the form shown in Fig. 1, and in which certain of the automatic controls are correspondingly altered; and

Fig. 3 is a view in elevation of the purifier 55 for the gas shown in both Figs. 1 and 2.

The gas generating system, embodying this invention, comprises broadly a gas producer, a purifying mechanism for the generated gas, a work-device utilizing the gas and automatic means for controlling the generation of the gas.

Any suitable type of producer may be used. In Fig. 1 is illustrated a producer which comprises a cylindrical shell 10, the lower part or zone of which is adapted to contain a fuel bed and the upper part or zone a fuel reservoir.

The lower part, that is the gas generating zone, which, during operation, contains the fuel bed, has a cylindrical lining 11 of heat and wear resisting material, 70 backed by suitable heat insulating material 12.

The lining 11 preferably consists of fire clay, and may be in the form of a unitary cylindrical tile or may consist of a plurality of brick which when in position constitute a cylindrical lining member; the layer of heat insulating material which fills the space intervening between the metallic shell 10 and the lining 11 being preferably a mixture of the material, known commercially as "sil-

o-cell", which is composed principally of kieselguhr and cement. Any other material for forming the lining may be used if desired, but, for general operation, the lining 11

should have small heat capacity, so that, upon starting, it will be quickly brought up to operating temperatures. That is the construction should be such that the blowing up or starting period will be of short duration.

In a gas producer of large size the heat capacity of the fire brick lining is a matter of comparative indifference, but in gas producers such as are suitable for domestic use, in

which the size is comparatively quite small, the heat capacity of the lining becomes a matter of considerable importance. In the gas producer illustrated in the drawing the internal diameter of the generating zone, that is,

of the lining 11, is less than ten inches, say, for example, about five inches. In a pro-

90

95

99

100

ducer of such small size it has been found that the heat capacity of the lining should be small; and very satisfactory operation has been obtained where the thickness of the fire brick lining 11 does not exceed two inches. By using a fire brick lining of a thickness of from one to two inches, backed by a layer of heat insulating material of from four to five inches, the gas producer can be brought up to substantially maximum gas making conditions with a blowing up period ranging up to fifteen minutes.

The lining 11 need not necessarily be of fire clay. If desired this lining may be of a suitable metal capable of withstanding oxidation and deterioration of high temperatures, such metals, for example, as some of the commercially well known alloys of chromium and nickel. Also the heat insulating material 12 may be other than a mixture of silocel and cement, as described above, as any suitable insulating material may be used. Where a mixture of silocel and cement is used satisfactory results may be obtained when they are in the proportions of substantially four parts of silocel to one part of cement. Except for the fact that suitable heat insulating material does not ordinarily sufficiently withstand the abrading effect of the fuel bed to give long life the lining 11 could be entirely dispensed with and the gas generating zone provided only with a lining of heat insulating material. A lining of charcoal, or analogous carbonaceous material, also functions very well,—it being in some ways superior to the lining illustrated in the drawing and described above.

The lining within the gas generating zone rests upon a bottom plate 13, which closes the lower end of the shell 10, this plate being in turn supported, by means of bolts 14, from angle irons 15 permanently attached to the shell 10, as by welding or riveting. A passage is formed in the lining 12, which connects with the lower end of the gas generating chamber 16, within the cylindrical lining 11, to form an ash pit 17, and registers with an opening 18 formed in the shell 10 to provide access to the ash pit. The fuel bed within the gas generating chamber 16 is supported by a grate 19, which consists of a circular perforated plate supported by a plurality of legs 25, preferably three in number. One of the legs 25 is suitably extended to form a handle, by means of which the grate may be inserted into position within the ash pit or withdrawn therefrom, through the ash pit opening 18. The construction of the grate is such that when in position within the ash pit it is completely out of thermal contact with the metallic shell 10 of the producer. As is evident from the drawing, the bottom plate 13 is out of thermal contact with the shell of the producer, this plate being supported by the bolts 14 which are themselves

out of thermal contact with the shell of the producer. In addition the grate, since its thermal connection with the plate 13 is only through the legs 25, is almost completely heat insulated from the bottom plate 13. By means of this construction the loss of heat from the fuel bed, because of conduction thereof through the metal of the grate to the metallic shell 10 and radiation from the metallic shell 10 into the atmosphere, is almost entirely prevented. This construction has a very material effect in the starting and running of the gas producer; and not only does it decrease the starting or blowing up period, but it also contributes very materially to the more satisfactory operation of the producer, permitting of the generating of gas of better quality.

The upper end of the producer is closed by means of a top 30, which is positioned within the shell to form a water receiving trough 31. The top 30 has a fuel supply opening 32 therein surrounded by the upstanding flange 33, which has a cover 34 cooperating therewith, the lower edge of the cover extending down into the trough 31. During operation the trough 31 contains a supply of water, which functions as a seal to prevent the inflow of air into the producer through the fuel supply opening. Depending from the top 30 is a cylindrical flange or shell 35 which is spaced from the metallic shell 10 and extends downwardly to within a short distance of the top of the lining within the gas generating zone. Fuel for the producer is introduced through the opening 32 into the space within the upper part of the producer, that is, the space within the cylindrical depending shell 35, which acts as a fuel reservoir, the upper end of the fire brick lining 11, and layer of heat insulating material being inclined so that fuel within the reservoir 35 will readily pass downwardly, under the action of gravity, into the generating zone 16 to replace the fuel consumed during operation of the producer. The reservoir 35 can be proportioned to give any suitable capacity, and to thus permit of any reasonable period of operation of the producer without replenishing the supply of fuel. As illustrated the capacity of the fuel reservoir is sufficient to permit of operating the producer at full load for about six or seven hours. Leading off from the space between the shell 35 and the shell 10, and adjacent the top of the producer, is a gas off-take pipe 40, to which is connected a blower 41. This blower is preferably of the centrifugal type, and adapted to give a constant pressure at the delivery orifice thereof for any given speed.

The gas producer described is of the suction type, the blower or pump 41, during operation, functioning as a vacuum pump to cause air to pass into the ash pit from the saturator through pipe 58, thence upwardly

through the fuel within the generating zone 16, to generate producer gas, and thence out through the offtake pipe 40 and through the blower 41 which delivers it under pressure to a delivery main, and so to the place of use. 5 But any suitable type of producer whether suction operated or pressure operated may be used, although such a suction producer as illustrated is preferred. If it is desired to use 10 a pressure producer, the blower 41 would be connected to the ash pit and caused to function as a pressure pump, instead of a vacuum pump, to thus force air and moisture through the fuel bed and out through the offtake to the 15 delivery main. As is well known, for satisfactory operation of a producer the air which passes through the fuel bed should contain a substantial amount of moisture. This is true whether the producer be operated under 20 suction or under pressure. For purposes of description, therefore, the passing of air alone, or air and moisture in desired proportions, through the fuel bed to cause the generation of gas, whether under suction, under 25 pressure or under natural draft, is designated generally as "blasting the fuel bed." The term therefore refers generally to the operation of passing air, or air and moisture, through the fuel bed to cause the generation 30 of gas.

The producer as thus far described is substantially identical with the producer shown in the application of Harry F. Smith filed July 24, 1920, Serial No. 398,749.

35 As the generated gas passes upwardly through the space between the shells 10 and 35, to the offtake, a large part of the sensible heat of such gas is transmitted to the metallic shell 10. In the type of producer shown 40 in the above referred to application this heat is partly radiated into the atmosphere, and partly transmitted into the water within the vaporizer. In the form of producer shown herein the upper part of the producer 45 is surrounded by a jacket 46, adapted to contain water. A considerable part of the heat of the generated gas is transmitted through the shell 10 into the water within this jacket. Leading off from the jacket, adjacent its top, 50 is a pipe 47 which is also connected to the upper end of a hot water storage tank 48. Leading off from the jacket 46 adjacent the lower end thereof is a pipe 49 which opens into the tank 48 adjacent the lower end thereof. 55 By means of this construction the water within the jacket 46, as it is heated, passes upwardly through the pipe 47 into the tank 48, the cooler which at the bottom of the tank 48 passing 60 downwardly through the pipe 49 into the jacket, a circulation thus being established, so that the sensible heat of the generated gas is used to heat a supply of water for general use, the tank 48 being connected through the 65 pipe 50 to any desired place of use. The tank

48 also has a supply pipe 51 leading thereto from any suitable source of water.

Leading off from the top of the tank 48 is a pipe 52 which opens into a saturator. This saturator consists of a metallic shell 55 having a series of grids, or baffles, 56 therein. The saturator shown is like that shown in the patent to Harry F. Smith No. 888,359 issued May 19, 1908. The grids preferably consist of boards arranged in the form of checker-work so that the hot water entering the saturator at the top through the pipe 52 will flow downwardly therethrough spreading out over the grids 56 and thus presenting a large surface of water to the atmosphere 80 within the saturator. In the shell of the saturator below the grids 56 is an opening 57, connecting the space within the saturator to the atmosphere. Opening out of the top of the saturator, above the grids 56, is a pipe 58 which passes into the ash pit 17 and terminates therein. A door 20 is provided for the ash pit opening 18, which is normally closed during operation so that all the air introduced into the generating zone must pass through the saturator. As the air passes 85 through the opening 57 and up through the grids in the saturator to pass off through the pipe 58 to the ash pit it will reach a condition of saturation with moisture at the 90 temperature which prevails within the saturator. As set forth in the above referred to patent the amount of moisture which is taken up by the air is a function of the temperature of the air. Thus by varying the amount of 95 hot water which is introduced into the saturator through the pipe 52, the temperature of the air within the saturator can be correspondingly varied, and the amount of moisture which is supplied to the producer controlled. Located within the pipe 52 is a valve 100 58 by means of which the amount of water supplied to the saturator can be varied as desired. Leading off from the bottom of the saturator, below the grids, is an outlet pipe 105 59 through which the water fed to the saturator passes off. A centrifugal pump 60, preferably operated by an electric motor 61, connected by the conductors 63 and 64 to a source of current, is connected to sections of 110 the pipe 59 so that the water fed through the saturator may be passed back into the jacket 46. Any suitable form of pump and means of operating that pump may be used in place of the centrifugal pump 60 and electric motor 61 shown. By using a centrifugal pump, 115 however, and a constant speed motor the water returned to the jacket 46 may be returned thereto under the proper pressure for causing satisfactory circulation within the system thus far described. If desired the pump 60 and operating motor may be entirely dispensed with and the water fed through the saturator wasted.

Connected to the outlet of the blower 41 is a 120

pipe 65 through which the gas from the blower is delivered under pressure to the purifier 66. The pump or blower 41, as shown, is of the conventional centrifugal type, and is driven by a constant speed motor 42 connected by means of conductors 43 and 44 to a source of electric current, the source shown being the battery 45. The motor and blower operating at constant speed will tend to give a constant pressure at the outlet of the blower irrespective of the volume of gas delivered. By properly regulating the speed of the blower or pump 41, therefore, the pressure of the gas delivered from the pump may be controlled as desired. And this delivery pressure should always be greater than the maximum pressure to be attained in the gas delivery main. If preferred a positive pump and recirculating pipe such as shown in Fig. 2 may be used in place of the centrifugal blower illustrated.

From the blower the gas passes, through the pipe 65, under suitable pressure to the purifier 66, which consists of a cylindrical metallic shell adapted to contain a layer of saw-dust, shavings, or similar material, for removing impurities from the gas. In the generating system illustrated the producer is intended to operate upon charcoal, coke, or analogous fuel, the gas from which contains comparatively few impurities. If a fuel such as bituminous coal were used a different type of purifier would also be used, since the comparatively large quantities of tar which are formed during the generation of gas from bituminous coal would, in most cases, make desirable a type of purifying or cleaning apparatus adapted to give better cleaning of such a gas than is the purifier shown. A purifier such as shown in the patent of Harry F. Smith No. 1,099,773, issued June 9, 1914, would function satisfactorily for this purpose. Located within the purifier, between the opening of the pipe 65 thereinto and the opening therefrom into the outlet pipe 67 is a baffle member 68 which, as shown more clearly by Fig. 3, is in the form of an inverted trough member of V shape, extending throughout the length of the purifier, the positioning being such that the gas entering the purifier through the pipe 65 is forced to take a circuitous path through the mass of purifying material, as it passes to the outlet 67, to thus increase the time of contact of the gas with that material. The baffle 68 is supported by means of a rod 69, which also assists in the retaining in place the closure members 70 and 71 which close two openings in the end of the purifier through which purifying material may be introduced or withdrawn. These two closure members are mounted upon a bar 72 through which passes one end of the rod 69 and a separate retaining rod 73. The rod 69, and the retaining rod 73 have nuts threaded upon the ends thereof

and so positioned that by loosening them the bar 72 and its cooperating closure members 70 and 71 may be removed, and by tightening them, with the bar and cooperating closure members in position, these closure members will be held in place. In order to prevent leakage each of the closure members 70 and 71 has a packing member 74 associated therewith, which packing may be of any desired character. For retaining the baffle 68 in proper position within the purifier, and to prevent its moving about the supporting rod 69, two stop members 75 are provided. As shown in the drawing these stop members consist of bolts which are threaded through suitable openings in the end of the purifier and are so positioned as to restrain the baffle members in the desired setting.

If desired a purifier containing, as the purifying material, a layer of finely divided carbonaceous material, such as charcoal may be used, purifiers of this type having been found to function very satisfactorily under actual operating conditions. Such type of purifier is clearly disclosed in the application above referred to.

The gas outlet pipe 67 opens into a valve fitting 80. Connected to the valve fitting 80, is a gas delivery main 81 and a vent pipe 82. Located within the valve fitting 80 is a valve member 83 adapted to cooperate with each of the ports to which the delivery main 81 and vent pipe 82 are connected. Any suitable type of double beat valve will function satisfactorily, and the type of valve illustrated in the drawing merely shows one suitable form. This valve comprises a valve stem 84 to which are pivotally attached two opposing disc members 85 one of which is adapted to cooperate with the port to which the delivery main is connected and the other with the port to which the vent pipe is connected. The arm 84 is rigidly attached, within the fitting 80, to an operating shaft 86, pivotally mounted in any suitable manner within the walls of the valve fitting 80 but with one end preferably extending out through the valve fitting, the said one end of the shaft 86, without the fitting 80, being rigidly attached to the operating arm 87. The delivery main 81 is adapted to lead the gas to any desired place of use, one suitable type of work device, illustrated conventionally, being a cook stove 90, of any usual construction, shown as having a plurality of burners 91 connected to the pipe 92 which is in turn connected to the delivery main, and through which gas is supplied to the burners, valves 93 being provided for controlling the flow of gas to said burners.

Leading off from the delivery main 81 is a branch pipe 95 which opens into the lower bell 96 of a gasometer, the upper bell 97 of which is movable. Pivotal mounted adjacent the gasometer is a bell crank lever 100 one arm of which cooperates with the upper

bell of the gasometer, the other end thereof being operatively connected to the arm 101, which is in turn pivotally connected to the operating lever 102 of the valve 103. The valve 103 is located within the delivery main 81 and movement thereof tends to increase or decrease the effective opening through that main, and the amount of gas which flows past that valve into the delivery main beyond the 10 valve will be dependent upon the effective opening through the main at that point. The gasometer floats on the delivery main line so that the pressure therein will correspond to the pressure of the gas in the delivery main 15 beyond the valve 103. If the pressure tends to build up in the delivery main it will tend to correspondingly build up in the gasometer to raise the upper bell thereof and thus actuate the valve 103 to cut down the effective 20 opening therethrough and thus return the pressure to the desired predetermined condition. If the pressure in the delivery main, beyond the valve 103, tends to fall, as would be true where an extra work device is cut in, 25 the pressure in the gasometer would also tend to correspondingly decrease and the upper bell thereof would fall to move the valve 103 to increase the effective opening therethrough and thus bring the pressure in the delivery 30 main back up to the predetermined normal. The gasometer thus functions as an automatic regulating device for maintaining constant the pressure of the gas in the delivery main, beyond the valve 103, and thus to maintain constant the pressure of the gas at the work device.

Also associated with the gasometer is a switch 110 for controlling operation of the motor 42, which drives the blower 41. As 40 stated above, the motor 42 is operated by means of electricity from any suitable and desired source, this source of electricity being illustrated as a storage battery 45, though, of course, any other source of current may be utilized. The switch 110 is connected within the conductor 43 connecting the motor 42 and the battery 45. This switch is so located that when the upper bell of the gasometer rises to a predetermined point the switch will 45 be opened to stop the motor, and when the gasometer falls below a predetermined fixed point, and so long as it remains below this predetermined fixed point, the switch will be closed, the switch being urged into closed 50 position by the spring 111. As shown, upward movement of the gasometer bell, a suitable distance, brings the upstanding lug 112, carried by the bell crank lever 100 into contact with the switch 110 to open that switch. This 55 is only one, of many possible, means of opening the switch upon upward movement of the gasometer bell, and is merely illustrative of a satisfactory embodiment of the invention. Any other type of switch and mechanism for opening that switch upon the build- 60

ing up of sufficient pressure within the delivery main would be satisfactory. A check valve 104, is positioned in the delivery main 81, between the pipe 95, the pipes leading to the work devices and the valve fitting 80, and is adapted to permit the free flow of gas from the fitting through the main when the blower 41 is operating but to prevent back flow from the main and gasometer when the blower is not operating. As shown the valve consists of a conventional flap valve member which opens under pressure from the fitting and closes under the action of gravity when such opening pressure is removed.

Leading off from the pipe 67, between the purifier and the valve fitting 80 is a branch pipe 115, which terminates within a hot water heater 116 within which is located a hot water coil 117, of conventional construction, one end of this coil being connected, through the pipe 118, to the lower end of the storage tank 48, and the other, through the pipe 119, to the upper end of the storage tank 48. The pipe 115 terminates within the heater 116 below the coil 117, the end of the pipe constituting a burner 120. Located adjacent the burner 120 is a spark plug 121, one terminal of which is connected to one of the high tension terminals of a conventional spark coil 122, by means of the conductor 123, the other terminal being connected to the other high tension terminal of the spark coil, either directly or by grounding, as illustrated, by means of the conductor 124. The low tension terminals of the spark coil 122 are connected in series with the motor 42, one terminal being connected to the conductor 43 through the conductor 125, and the other connected, through the conductor 126, to one terminal of a thermostatic switch, included within the spark coil circuit, the other terminal of which is connected, through the conductor 133 to the other motor conductor 44. One member of this switch consists of a thermostatic element 127, mounted within the wall of the hot water heater 116, suitable insulation 128, which may be of any desired character, being provided to electrically insulate this member of the switch from the wall of the hot water heater. Cooperating with the free end of the thermostatic element 127 is a contact member 129, which is also mounted within the wall of the hot water heater and suitably insulated therefrom, by means of the insulating member 130. The thermostatic element 127 is of such character that its curvature changes with its temperature, and is so arranged that at normal temperatures it will contact with the member 129, but when its temperature is raised, as will occur when the gas escaping through the burner 120 is ignited, and so long as this gas is burning, it will be deformed and held out of contact with the member 129. This construction is such that when the plant is idle the thermo-

70

75

100

105

110

115

120

125

130

static member 127 is so positioned that the circuit through the low tension coil of the spark coil is closed, in so far as this thermostatic switch is concerned. But in order to completely close the circuit through the low tension coil of the spark coil the switch 110 must also be closed. That is to say, when both the thermostatic switch, and the switch 110 are closed there will be a flow of current from the battery 45 through the low tension coil of the spark coil, but if either of these switches is open there can be no flow of current through the coil. So, even though the thermostatic element 127 is normally positioned, when the plant is idle, so that it contacts with the member 129, there will be no actuation of the spark plug, for under these same conditions the switch 110 is normally open. For when the use of gas at the work devices, as for instance at the stove 90, is entirely discontinued, the blower 41 will continue to operate to cause the generation of gas, until the pressure becomes sufficiently high to raise the upper bell 97 of the gasometer to open the switch 110, thus stopping the motor 42 and the blower 41 connected thereto.

Also cooperating with the thermostatic element 127 is a contact member 131 mounted, within the insulating member 130, in the wall of the hot water heater 116. The thermostatic element 127 is connected, as stated above by means of the conductors 133 and 44 to one terminal of the battery 45. The contact member 131 is connected, by means of the conductor 134, to the conductor 43 and thus to the other terminal of the battery 45. Interposed in the conductor 134 is a solenoid 140, which is mounted in any suitable manner, adjacent the valve fitting 80, the form of mounting not being shown since any desired means of mounting this coil may be utilized. The core 141 of this solenoid is operatively connected to the operating arm 87 of the valve member 83, a spring 142 being associated with the operating arm 87, and the core 141, so that it normally urges the valve member 83 to shut off connection between the delivery main 81 and the delivery pipe 67, and to connect the delivery pipe 67 to the vent pipe 82. The core 141 is preferably connected to the arm 87 by means of a conventional slot-and-pin construction, designated generally by the numeral 143. When the solenoid is energized, however, the core thereof is moved, against the resistance of the spring 142 to move the valve member 83 to close off connection between the delivery pipe 67 and the vent pipe 82 and to connect the delivery main 81 to the delivery pipe 67. The thermostatic element 127 is so constructed, and positioned, that under normal temperature conditions, as when the plant is idle, or when gas is not being burned at the burner 120, this element will be out of

contact with the contact member 131. That is when the plant is idle, or, even though the plant is operating but no gas is being burned at the burner 120, under which conditions the temperature of the thermostatic element 127 will be substantially the same as the atmosphere, it will be out of contact with the member 131 so that the solenoid 141 will not be energized, and the spring 142 will hold the valve 83 in such position as to cut off connection between the pipe 67 and the delivery main 81, that is disconnect the gas producer from the gas delivery main, and connect the pipe 67 to the vent pipe 82, that is connect the gas producer to the vent pipe. At such time, as set out above, the element 127 will contact with the terminal element 129. But as soon as the temperature of the thermostatic element is raised sufficiently as will happen when gas is burned at the burner 120, this element will be distorted to cause it to contact with the member 131, with a resulting energizing of the solenoid 141 to move the valve 83 to cut off connection between the vent pipe 82 and the offtake pipe 40, and to connect the delivery main 81 with the offtake pipe 40.

The gas generating system described is automatic in its operation, and after a fire is once started within the generating chamber 16, the plant will function automatically with no other attention than the addition of fuel to the reservoir, and the removal of ashes from the ash pit, at suitable intervals, and such other incidental attention as is necessary in the satisfactory operation of the motors, and the like.

Presuming that the plant is standing idle, after a prior period of use, and that the fuel bed within the gas generating zone 16 is smouldering or incandescent, the pressure of gas within the gasometer, from the prior period of operation will be sufficient to hold the upper bell 97 in extreme elevated position, the switch 110 thus being open. With the switch 110 open neither the motor 42, the motor 61, the solenoid 140 nor the spark coil 122 will function. Under these circumstances there will be no generation of gas, and the check valve 104 beyond the valve fitting 80, in the delivery main 81, will be closed preventing the back flow of gas from the gasometer and delivery main. Consequently there will be no gas passing through the pipe 115 to the burner 120, and the thermostatic element 127 will not be subjected to any outside heating effect. Under these circumstances the thermostatic element will be in contact with the member 129 and out of contact with the contact member 131. Thus the solenoid 141 will not be energized and the spring 142 will hold the valve member 83 to close the connection between the gas delivery main 81 and the delivery pipe 67, and thus to interrupt the connection between the de-

livery main 81 and the gas offtake pipe 40, and in the same manner connect the offtake pipe 40 to the vent 82. As soon as the operation of any work device is commenced, as for instance by lighting one of the burners 91 of the stove 90, some gas will be withdrawn from the main 81, to decrease the quantity of gas within the main and gasometer and to thus decrease the pressure therein so that the upper bell 97 of the gasometer will fall and cause the switch 110 to close. This causes the motor 42 to function to operate the blower 41. It also causes the motor 61 to function to supply moisture to the air blast being drawn through the fuel bed within the gas generating chamber by the operating motor 41, the resulting gas, because of the positioning of the valve member 83, passing off through the vent pipe 82. At the same time the spark coil 122 will be energized to cause spark plug 121 to function. As the gas passes off through the vent 82 a portion of the gas will also pass through the pipe 115 to the burner 120. If the plant has been standing idle for a substantial period the first gas which passes through the offtake 40 will probably be of such poor quality, that is of such low heat value, that it will not support combustion and the fuel bed must be subjected to a suitable blowing up with air to bring it back to a condition of good gas generation. This blowing up or starting period will vary according to the condition of the fuel bed at the time. If the plant has been standing idle overnight, say, it will probably require, in a gas producer of the size referred to above, a blowing up period of from five to ten minutes, where the fuel used is charcoal. With other fuels the blowing up period will also vary according to the character of the fuel. As soon as the generation of gas is started, however, the sparking of the spark plug 121 is also started, and when the gas generated becomes of such quality that it will support combustion, it will ignite from the sparks, and will continue to burn so long as it escapes from the burner 120. The heat of the burning gas, acting upon the thermostatic element 127, will cause that element to distort to open the spark coil circuit and close the solenoid circuit. As a result the spark plug will cease to function, and the valve member 83 will be moved to disconnect the vent pipe 82 from the pipe 67, and connect the delivery main 81 to the offtake pipe through the pipe 67. The generated producer gas will then be forced through the delivery main 81 to the place of use. As stated above the construction is such that the pressure of the gas as delivered from the blower will at all times exceed the maximum pressure attained in the delivery main regardless of the quantity of gas delivered. But the flow of gas through the delivery main 81 is subject to control by the position of the valve 103, and the posi-

tioning of this valve is in turn controlled by the positioning of the gasometer bell 97. As more or less work devices are cut into or out of service, therefore, the quantity of gas used will vary, but the pressure within the delivery main 81, beyond the valve 103 will be maintained substantially constant, by means of the gasometer which, together with the valve 103 really functions as a pressure regulating device. If for any reason, however, the pressure of the gas within the delivery main 81 should go up, the upper bell of the gasometer would immediately rise in accord with this increased pressure, and if the pressure builds up sufficiently high, would open the switch 110 to stop the blower. This is exactly what happens when all of the work devices are stopped, the blower running long enough to generate sufficient gas to fill the gasometer. And as set out above the gasometer is of such size that it will store just enough gas to run a small work device, such as one burner of the stove, for the blowing up period of the producer.

The valve 58, within the pipe connecting the hot water tank 48 to the saturator 55 has an operating stem 62 connected thereto which is also operatively connected to the arm 101. As a result the effective opening of the valve 58 will be varied to accord with the effective opening of the valve 103, which in turn is dependent upon the quantity of gas passing through the delivery main 81. Thus the amount of moisture supplied to the gas generating chamber is varied to accord with the quantity of gas being generated. This construction is such that when the upper bell 97 of the gasometer rises to extreme upper position, to open the switch 110, and stop the generation of gas, the valve 58 will be completely closed, to prevent the flow of water from the hot water tank 48 to the saturator 55.

While the burner 120 is shown in connection with a hot water heater, this is not essential and the heater 116 may be entirely dispensed with if desired, and the tank 48 or any other heating tank depended on for hot water supply. In such construction the operation of the thermostatic contacts would be just the same. And of course efficiency is gained by utilizing the heat needed for operating these contacts for helping in the maintenance of a supply of hot water rather than wasting such heat to the vent.

The form of apparatus shown in Fig. 2 is fundamentally quite similar to that already described. The gas producer, as shown, consists of a shell 200, which has in the lower part thereof, designated generally 201, the gas generating zone, the ash pit, and the grate, similar in construction, and function, to the corresponding parts of the producer shown in Fig. 1, and described above. The method of supplying moisture to the air

blast, is different from that described above, the trough 203 having a cover member 204 the depending walls of which extend down into the trough 203 and enclose within them a substantial part of the water within the trough. Extending downwardly from the trough 203, through the fuel reservoir, contained within the depending flange 205, and passing through the lining of the generating zone, to terminate within the ash pit, is a pipe 206. The cover member 204 has an opening 207 therein. The ash pit has a door 208 which normally closes the opening thereto through which the grate is introduced and removed. As the blower 210 operates air is drawn in through the opening 207, over the water in the trough or vaporizer 203, and downwardly through the pipe 206 into the ash pit, and thence through the fuel bed. As the gas generated passes from the fuel bed it passes out through the space between the shell 200 and the depending flange 205, to the offtake pipe 209. During operation of the producer, therefore, the temperature of the water within the trough 203 is raised to cause vaporization thereof, and as the air is drawn in through the opening 207 and down through the pipe 206 vapor is taken up by the air and carried with it into the generating zone of the producer. The type of producer illustrated in Fig. 2 is similar in construction, and operation to that shown in the above referred to application of Harry F. Smith, Serial No. 398,749, filed July 24, 1920.

35 Mounted within the offtake pipe 209 is a blower or exhauster 210. This blower, if desired, may be of the centrifugal type described above in connection with the system illustrated in Fig. 1. But the blower shown is of the conventional gear impeller type, that is, it is a positive pump. The construction of this blower is not shown in detail since blowers of this type are well known and any satisfactory type commercially available may be used. Or if preferred, a reciprocating or plunger type pump may be used. This blower is belt driven by an electric motor 211, preferably operated at substantially constant speed, connected to a suitable source of current by the conductors 212 and 213, the source of current illustrated being a storage battery 214, though any other suitable source of current may be used. Connected to the delivery of the blower is a pipe 215 which opens into a purifier 216 for the gas, identical in construction with that described above. Connecting the pipe 215, beyond the blower, with the offtake pipe 209, in advance of the blower is a recirculating pipe 217, in which is inserted a pressure operated valve 218. This valve may be of any desired type so long as it is so constructed as to open when the gas pressure in the pipe 215 rises to a predetermined point and to remain open so long as such predetermined pressure is exceeded. And this

predetermined pressure should at all times, during operation of the blower, exceed the maximum pressure attained within the gas delivery main. This construction is such that when the predetermined gas pressure in the delivery pipe 215 is exceeded part or all of the gas will be recirculated through the pipe 217 and pump 210, so that the pressure of the gas delivered by the pump will not exceed the predetermined maximum. The pressure regulating valve shown is of conventional type, the pressure at which it will open being regulable by proper manipulation of the threaded plug 219 which upon being moved in or out correspondingly varies the tension of the spring 220, and thus varies the pressure necessary for causing the valve to open.

Leading off from the purifier 216 is a pipe 225 to which is connected a valve fitting 226, having two valves, 227 and 228 therein, located, one at each side of the place where the pipe 225 opens into the fitting. Connected to one end of the fitting 226 is a vent pipe 229, and to the other end is a gas delivery main 230, the valve 227 being so positioned within the fitting 226 that it can cut off connection between the pipe 225 and the pipe 230, or open connection between these two pipes, and the valve 228 so positioned that it can cut off connection between the pipe 225 and the vent pipe 229, or open connection between those pipes. The pipe 230 passes through the wall, of a gasometer 235, and terminates within the upper bell 236 thereof. Also terminating within the upper bell of the gasometer is a continuation of the delivery main, which also passes through the wall of the gasometer and is connected to suitable work devices. Suitable liquid 237 is contained within the gasometer, which, in the form of invention illustrated in Fig. 2, is of considerable size.

In any gas producer there is a certain minimum amount of air blast which must pass through the fuel bed in order to maintain the generation of satisfactory gas, that is gas having sufficient heat value. If the air blast falls below this predetermined minimum the quality of the gas will fall off, and therefore each producer has a minimum capacity, and requires a minimum blast during operation to produce suitable gas for use in a work device. In a producer of the size shown, the size mentioned above in connection with the description of Fig. 1, this minimum capacity is quite small, but a single work device, such as a burner of a gas stove or a gas light, does not require, in its operation, an amount of gas which is equivalent to that generated when the producer is being operated at minimum capacity. It is sometimes found desirable, as where gas is to be supplied for domestic or home use, to provide gas storage of considerable capacity. This storage capacity should be sufficiently great to provide that quantity

of gas which will permit of operating over an extended period a work device using less gas than the minimum capacity of the producer. It is estimated that to provide sufficient gas to operate a single incandescent light, such as is frequently burned overnight in a bath room, say, will require a storage capacity of about 300 cubic feet. The gasometer 235 in this modification of the invention, 5 is adapted to have such storage capacity. The gasometer in the modification described above, and illustrated in Fig. 1, has sufficient storage capacity to supply gas for a work device during the blowing up period of the 10 producer, but has not sufficient capacity to operate such a work device over an extended period of time. In other words, in the modification shown in Fig. 1 the generator will function almost continuously when gas is being used at a work device. But in the modification shown in Fig. 2 sufficient storage is provided so that one or more work devices 15 may be operated for a considerable period without the generation of gas being started. 20 The operation of the producer in the modification shown in Fig. 2 is more or less intermittent while the operation of the producer shown in Fig. 1 is practically continuous.

The upper bell 236 of the gasometer has 25 connected thereto the conventional balance-weight 238, which is carried upon the end of a cable 239 running over the conventional pulley 240. Also carried upon the upper bell 236 is a standard 241 having two stops 242 and 243 thereon, which stops are positioned 30 to cooperate with the switch 245. The stop 242 is so positioned that it will close the switch 245 when the gasometer bell 236 reaches a predetermined lower position, 35 while the stop 243 is positioned to open the switch 245 when the gasometer bell reaches a predetermined upper position. The switch 40 245 is within the conductor 212, connecting the motor 211 to the battery 214, so that when this switch is closed, the motor and the 45 blower driven thereby, will operate to cause the generation of gas, but will not operate when the switch 245 is open.

Leading off from the valve fitting 226, 50 between the valves 227 and 228, so that it is connected to the pipe 225 regardless of the setting of the valve 227 and 228 is a pipe 250 which terminates in a burner 251, located within the lower part of a hot water heater 55 252, similar to the hot water heater 116 shown in Fig. 1, the hot water coil 253 therein being connected to a conventional hot water storage tank, not shown, through the pipes 254 and 255. This hot water heater 60 also has a vent pipe 256 which is connected to the vent pipe 229. Mounted in the wall of the hot water heater 252 is a spark plug 260, one terminal of which is connected, by means of the conductor 261, to one of the 65 high tension terminals of the spark coil 262,

which is shown conventionally, any good type of spark coil serving, the other terminal of the spark plug being connected to the other high tension terminal of the spark coil, either directly or by grounding as shown in the drawing, by the conductor 263. This spark plug is positioned adjacent the burner 251, so that when functioning, it will tend to ignite any gas escaping through the burner 251, and will ignite that gas if it is of sufficiently good quality to support combustion. The terminals of the low tension coil of the spark coil 262 are connected in series with the motor 211, so that flow of current through the low tension coil of the spark coil 262 is 70 controlled by the switch 245. One terminal of the low tension coil of the spark plug is connected to the motor circuit 212 by the conductor 264. The other terminal is connected through the conductor 265 to one terminal 75 266 of a thermostatic switch, the other terminal 267 of which is connected through the conductor 268 to the motor circuit conductor 213. This switch comprises a thermostatic element 267 mounted in the wall of the 80 hot water heater 252, and suitably insulated therefrom by means of insulating material, illustrated conventionally at 269. The thermostatic element 267 cooperates with the contact member 266, which is mounted in the 85 wall of the hot water heater 252, and suitably insulated therefrom by means of insulation shown conventionally at 270. This contact member is connected to the conductor 265. Mounted in the wall of the hot water heater, 90 and suitably insulated therefrom by means of the insulating member 270 is a second contact member 271 which is connected to the battery 214 by means of the conductor 272 and motor circuit conductor 212. Within the 95 conductor 271 is mounted the solenoid 275, the core of which is operatively connected to a member 276, which in turn is operatively connected to the operating levers 277 and 278, of the valves 227 and 228 respectively. 100 As illustrated the member 276 is merely a continuation of the core of the solenoid, and is connected to the two operating levers 277 and 278 by a pin and slot connection to permit satisfactory operation. The thermostatic element 267 is so positioned within the hot water heater, adjacent the burner 251, that it is subjected to the heat generated by the gas burning at that burner. The contact members 266 and 271 are so positioned, relative to the thermostatic element, that under normal, or atmospheric temperatures, as when there is no generation of gas, the element 267 is in contact with the member 266, but out of contact with the member 271. But 110 when at sufficiently higher temperatures, as when subjected to the heat generated by the burning of gas at the burner 251, this element is so distorted that it is held out of contact with the member 266, and is maintained 115 120 125 130

in contact with the member 271. It will be noted that in order for a flow of current to take place through the low tension coil of the spark coil 262, not only must the thermostatic element 267 contact with the member 266, but also the switch 245 must be closed. And the solenoid 275 will be energized so long as the switch 245 is closed and the thermostatic element 267 contacts with the member 271. The arrangement of the valves 227 and 228, and of the operating mechanism therefor is such that when the solenoid is not energized, as is the case whenever gas is not being burned at the burner 251, the valves 227 and 228 will be positioned to cut off connection between the generator and delivery main and to connect the generator to the vent pipe.

Leading off from the delivery main 230 is a branch pipe 290, which leads to an illustrative type of work device. This work device consists of a stove 291 having two burners 292, this stove, and the parts thereof, being illustrated conventionally inasmuch as any suitable form of stove may be used.

The operation of this device is quite similar to the operation of the modification described above. Suppose the plant has been idle for a substantial period, overnight say, and it is desired to start up in the morning. The storage gasometer will be full of gas, the upper bell 236 thereof being in sufficiently elevated position to hold the stop 243 in contact with the switch 245 to hold that switch open. At the same time the thermostatic element 267 will be contacting with the member 266, but because of the switch 245 being open the spark coil will not function. As gas is withdrawn from the gasometer, as upon lighting one of the burners 292, the pressure within the gasometer, and the delivery main, will decrease, and the upper bell of the gasometer will fall. The use of the gas stored in the gasometer will continue until sufficient gas has been withdrawn to cause such a decrease in the pressure that the stop 242 will be moved to close the switch 245. The closing of this switch immediately starts the motor 211, to drive the blower 210. This causes air to pass through the fuel bed within the gas generating chamber 201, and starts the blowing up of the producer, the resulting gas withdrawn by the blower 210 passing through the purifier and pipe 225 into the valve fitting 226. The thermostatic element 267 being cold the solenoid 275 is inoperative, and consequently, the valve 227 which controls connection between the pipe 225 and the pipe 230, which leads to the gasometer is closed, and the valve 228 which controls connection between the pipe 225 and the vent pipe 229, is open. As soon as the blowing up operation is started, therefore, the gas withdrawn from the generator will be vented to the atmosphere 65 through the vent pipe 229. At the same time

a portion of this gas will pass through the pipe 250 to the burner 251. As stated above the thermostatic element 267, under these conditions will be so positioned as to contact with the member 266. As soon as the switch 245 is closed, then, the spark coil 262 will commence to function and sparks will be emanated adjacent the burner 251, and when the gas becomes of sufficiently good quality these sparks will ignite it. The heat of the burning gas then causes such distortion of the thermostatic element as to move the member 267 out of contact with the member 266 and to bring it into contact with the member 271. This causes cessation in the functioning of the spark coil 262, and causes a flow of current through the solenoid 275. As the solenoid 275 is energized the core to which is connected the rod 276 will move longitudinally thereof to swing the valve 227 into open position and the valve 228 into closed position. And as long as gas continues to burn at the burner 251 the solenoid will remain energized and will hold the valves in this position so that the gas generated will pass into the gasometer and thence through the delivery main 230, and so to the work devices. In this modification a certain equilibrium condition may be reached during continued utilization of the gas at a work device so that the upper bell 236 of the gasometer may assume a midway position, acting as a pressure regulating device, the gas being used in a quantity equal to the maximum output of the blower 210. But ordinarily gas will be gradually stored up in the gasometer, causing the upper bell 236 thereof to rise, as the quantity in storage increases, to bring the stop 243 into such position as to open the switch 245 and stop operation of the producer.

The embodiments of the invention illustrated and described herein are primarily designed for the furnishing of gas for domestic or house purposes, such for instance as utilization in cook stoves, in gas grates, in gas lights, and the like. In a gas generating system adapted for such purposes the construction and operation should be such that minimum attention is required both for maintenance and for operation. The producer should be of such character as to require a comparatively brief blowing up period. Especially is this true in the modification shown in Fig. 1 in which the gas storage is of such capacity as to permit of operation of a work device only for a brief blowing up period. In the type of gas producer shown in each modification illustrated herein, the blowing up or initial blasting period is of brief duration, ranging during operation up to fifteen minutes, depending on how long a time has elapsed since the last previous operation of the generator. In order to secure this brief initial blasting period the lining

of the gas generating zone should be of small heat capacity, so as to be quickly brought up to a temperature condition approximating the average temperature attained during continued operation of the plant. The gas producer should also, to provide satisfactory operating conditions, that is the continued production of gas of suitable character or quality, be so constructed that heat losses into the atmosphere, from the fuel bed, are reduced to a minimum. Each of the generators shown herein is constructed to thus minimize the heat losses, the lining of the generating zone being provided with a thick layer of heat insulating material and the metallic grate being out of thermal contact with the metallic shell of the producer. This minimizing of heat losses not only gives a more satisfactory operation, but prevents heat losses from the fuel bed during the idle or standover period, so that the plant will start up, when the blower is operated, even after long periods of standby.

While the method herein described, and the forms of apparatus for carrying this method into effect, constitute preferred embodiments of the invention, it is to be understood that the invention is not limited to this precise method and these forms of apparatus, and that changes may be made in either without departing from the scope of the invention which is defined in the appended claims.

What is claimed is:

1. A gas generating system comprising a gas producer, adapted to contain a fuel bed of ignited carbonaceous material; electrically operated means for blasting the fuel bed in said producer to cause the generation of gas; a gas holder for subsequent use; means for introducing generated gas into said holder; and control means for automatically starting the electrically operated blasting means when gas is withdrawn from said holder.

2. A gas generating system comprising a gas producer, adapted to contain a fuel bed of ignited carbonaceous material, and having a minimum gas generating capacity; means for blasting the fuel bed in said generator to cause the generation of gas, said means being adapted to so blast the fuel bed that during operation thereof the generation of gas will be in excess of the minimum capacity of the generator; a delivery pipe connected to said generator for delivering gas to any desired place of use; a gasometer connected to said delivery pipe and of such size as to hold in storage sufficient gas to operate for a predetermined period a work device which utilizes during operation less than the minimum capacity of said generator; and means coacting with said gasometer for starting the blasting device when the quantity of gas in said gasometer falls to a predetermined minimum and stopping it when the

quantity of gas reaches a predetermined maximum.

3. A gas generating system comprising a gas producer, an offtake leading off from said producer; a vent pipe opening into said offtake; a delivery main opening into said offtake; and thermostatic means responsive to heat of burning of generated gas for automatically connecting the offtake to the vent pipe or to the delivery main, according to the quality of the generated gas.

4. A gas generating system comprising a gas producer, adapted to contain a fuel bed and having an offtake connected to a vent pipe and to a delivery main; a valve for closing either the vent pipe or the delivery main; mechanism for actuating said valve comprising a thermostatic switch, a burner positioned adjacent said switch, means for supplying a portion of the gas generated in said producer to said burner; and a water heater in heat transferring relation with said burner.

5. A gas generating system comprising a gas producer, adapted to contain a fuel bed; a delivery main connected thereto; a blower for blasting the fuel bed within the producer and forcing the resulting generated gas through the delivery main; the delivery pressure of the blower being maintained substantially constant and above the maximum pressure to be attained in the delivery main; a valve in said delivery main, and pressure responsive operating mechanism therefor adapted to automatically move said valve towards open or closed position to maintain uniform pressure in the delivery main beyond said valve, without affecting the operation of the blower; and means in combination with said pressure responsive means for starting the blower operating means when the pressure in the delivery main reaches a predetermined minimum and stopping it when it reaches a predetermined maximum.

6. A gas generating system comprising a gas producer; a water jacket around said producer, a hot water storage tank connected to said water jacket; a saturator for the producer, connected to the hot water storage tank, and means for automatically controlling the amount of water passing from the hot water storage tank into the saturator to accord with the load on the producer.

7. A gas generating system comprising a gas producer having a gas delivery main; a water jacket around said producer, a hot water storage tank connected to said water jacket; a saturator for the producer, a pipe connecting the hot water storage tank to the saturator, a control valve in said pipe; and actuating means for said valve adapted to control the amount of water passing into the saturator to accord with the load on the producer.

8. A gas generating system comprising a gas producer, having a delivery main; a pres-

- sure regulating valve within said delivery main, operating mechanism for said valve, comprising a gasometer, the upper bell of which is operatively connected to said valve so that as the pressure beyond said valve tends to vary the gasometer bell will tend to rise or fall to reposition said valve to maintain pressure in the delivery main beyond said valve constant; a saturator for the producer and means for controlling the supply of moisture to said saturator, said means being operatively connected to the upper bell of said gasometer so that as said bell rises or falls the setting of the saturator control valve is correspondingly varied.
9. A gas generating system comprising a gas producer adapted to contain a fuel bed, means for blasting said fuel bed to cause the generation of combustible gas, a delivery line for leading the generated gas to a place of use, a vent pipe for wasting to the atmosphere the gas generated during the initial blasting period of the producer to bring the fuel bed to good gas-making condition, an auxiliary starting reservoir for supplying gas to the delivery line, and means controlled by the auxiliary starting reservoir to control the main delivery line.
10. A gas generating system comprising a gas producer adapted to contain a fuel bed, means for blasting said fuel bed to cause the generation of combustible gas, a delivery line connected to the outlet of the producer, a valve within said delivery line; a vent pipe connected to the outlet of the producer, an auxiliary starting reservoir for supplying gas to the delivery line during the initial blasting period of the producer to bring the fuel bed to good gas-making condition, and automatic means operated by the auxiliary starting reservoir to control the positioning of said valve within the main delivery line.
11. A gas generating system comprising a gas producer adapted to contain a fuel bed, means for blasting the fuel bed to cause the generation of combustible gas, a delivery line connected to the outlet of the producer for delivering the generated gas to the place of use, a vent pipe connected with the outlet of the producer, an auxiliary starting reservoir for supplying gas to the delivery line during the initial blasting period of the producer to bring the fuel bed to good gas-making condition, and means for delaying delivery of the gas into the main delivery line until the gas generated during said initial blasting period is of proper quality.
12. A gas generating system comprising a gas producer adapted to contain a fuel bed, means for blasting the fuel bed to cause the generation of combustible gas, a delivery line connected to the outlet of the producer for delivering the generated gas to a place of use, a vent pipe connected with the outlet of the producer, an auxiliary starting reservoir for

supplying gas to the delivery line during the initial blasting period of the producer to bring the fuel bed to good gas-making condition, and a gas testing unit for automatically controlling delivery of gas from the producer to the delivery line to delay delivery into said line until the generated gas is of proper quality.

13. A gas generating system comprising a gas producer adapted to contain a fuel bed, means for blasting the fuel bed to cause the generation of combustible gas, a delivery line connected to the outlet of the producer for delivering the generated gas to a place of use, a vent pipe connected with the outlet of the producer, an auxiliary starting reservoir for supplying gas to the delivery line during the initial blasting period of the producer to bring the fuel bed to good gas-making condition, and a combined gas testing and hot-water heating unit for automatically controlling the connection of the delivery line to the outlet of the producer to delay delivery of gas from the producer into said line until the generated gas is of proper quality, and for thereafter heating the water in a hot-water supply system.

14. A gas generating system comprising a gas producer adapted to contain a fuel bed, means for blasting the fuel bed to cause the generation of combustible gas, a saturator associated with said producer, a delivery line connected to the outlet of the producer for delivering the generated gas to a place of use, a vent pipe connected with the outlet of the producer, an auxiliary starting reservoir for supplying gas to the delivery line during the initial blasting period of the producer to bring the fuel bed to good gas-making condition, and a combined gas testing and hot-water heating unit for automatically controlling the connection of the delivery line to the outlet of the producer to delay delivery of gas from the producer into said line until the generated gas is of proper quality, and for thereafter heating the water in a hot-water supply system, and means for supplying hot water from said hot-water system to the saturator of the producer.

15. The method in the generating of producer gas, which consists in intermittently blasting at a substantially constant rate a fuel bed of ignited carbonaceous material within an enclosing generating chamber, withdrawing the resulting generated gas from the generating chamber containing the fuel bed, forcing it under pressure to a work device through a delivery main, and temporarily interrupting the blasting operation when the pressure of the gas in the delivery main reaches a predetermined point.

16. A gas generating system comprising a gas producer adapted to contain a fuel bed; suction means for causing a blast of air and moisture to flow through said fuel bed to

cause the generation of gas; and means for automatically stopping said suction means when the demand for gas ceases, the normal operation of said suction means being unmodified by said automatic stop means during the period of operation of the suction means.

17. A gas generating system comprising a gas producer adapted to contain a fuel bed; a delivery main connected to the producer for supplying gas to any desired place of use, a gasometer floating on the delivery main; means unmodified by said gasometer during periods of operation for withdrawing the generated gas from the producer and forcing it under pressure through the delivery main; and means in combination with said gasometer for intermittently stopping and starting said withdrawing means as pressure of the gas in the gasometer fluctuates under load, above or below a predetermined normal operating pressure, and for maintaining said withdrawing means inoperative so long as the pressure of the gas in the gasometer exceeds a predetermined maximum pressure.

18. A gas generating system comprising a gas producer having an offtake into which opens a vent pipe and a delivery main; valve means for controlling the connection of said offtake with the vent pipe and with the delivery main, said valve means being adapted for positioning to connect either the vent pipe or the delivery main to the offtake, said valve means tending to normally assume a position to maintain the vent pipe in connection with the offtake; and thermostatic means coacting with said valve means to automatically actuate said valve means to assume a different positioning to disconnect the vent pipe from the offtake and connect the delivery main to the offtake when the gas being generated and withdrawn from the producer is of such quality that it will burn.

19. A gas generating system comprising a gas producer adapted to contain a fuel bed; a delivery main connected thereto; a blower for blasting the fuel bed within the producer and forcing the resulting generated gas through the delivery main, means for operating said blower, the delivery pressure of the blower being maintained substantially constant throughout operation thereof; a valve in said main, and operating mechanism therefor responsive to pressure conditions in the delivery main beyond the valve and adapted to automatically move said valve toward open or closed position to maintain uniform pressure in the delivery main beyond said valve without affecting the operation of the blower.

20. A gas generating system comprising a gas producer adapted to contain a fuel bed, a delivery line connected to said producer, means for blasting the fuel bed to cause the

generation of combustible gas and for forcing said gas through the delivery line, a saturator for supplying moisture to the blast for the fuel bed, a gas reservoir for controlling the pressure within said delivery line, and means operated by said gas reservoir for controlling the supply of moisture to the saturator.

21. A gas generating system comprising a gas producer adapted to contain a fuel bed, a delivery line connected thereto, means for blasting the fuel bed to cause the generation of combustible gas and for forcing said gas through the delivery line, a control valve within said delivery line, and a gas reservoir connected to said delivery line and operatively connected with said valve for controlling the positioning of said valve to control the pressure in the delivery line beyond said valve.

22. A gas generating system comprising a gas producer adapted to contain a fuel bed of ignited carbonaceous material, means for blasting the fuel bed in said producer to cause the generation of gas, means for supplying the generated gas to a work device, means for automatically starting the blasting means when the use of gas at a work device is begun, and means insuring that gas delivered to said work device is of combustible character.

23. A gas generating system comprising a gas producer adapted to contain a fuel bed of ignited carbonaceous material, means for blasting the fuel bed in said producer to cause the generation of gas, a vent pipe, a delivery main leading to a work device, a gas holder for supplying gas to said delivery main during the initial blasting period of said fuel bed to bring the same to good gas making condition, means operative when gas is withdrawn from said holder to automatically start said blasting means to bring the fuel bed to good gas making condition and to discharge the gas during this initial blasting to said vent pipe, and means operative to automatically divert generated gas into said delivery main when the gas becomes combustible.

24. A gas generating system comprising a gas producer, a delivery main connected to said producer for delivering generated gas to any desired place of use, a vent pipe connected to said producer, a by-pass for diverting a portion of the gas generated in said producer, a burner connected to said by-pass, an igniting agency for gas issuing from said burner, and thermostatic means responsive to heat of burning of generated gas at said burner for automatically connecting said producer to the delivery main and closing off connection between said producer and the vent pipe when the generated gas becomes combustible and burns.

25. A gas generating system comprising a gas producer, a delivery main connected to said producer for delivering generated gas

- to any desired place of use, a vent pipe connected to said producer, a burner, means for supplying generated gas to said burner, an igniting agency for gas issuing from said burner, thermostatic means responsive to heat of burning of generated gas at said burner for automatically connecting said producer to the delivery main and closing off connection between said producer and the vent pipe when the generated gas becomes combustible and burns, and means for automatically cutting out said igniting agency after the generated gas issuing from said burner is ignited and burns.
26. A gas generating system comprising a gas producer adapted to contain a fuel bed of ignited carbonaceous material, a work device, electrically operated means for blasting the fuel bed in said producer to cause the generation of gas and for supplying said gas under pressure to a work device, means for starting the electrically operated blasting means to cause the generation of gas, and means responsive to the burning of generated gas for automatically delaying the supplying of generated gas to said work device by said electrically operated blasting means until the generated gas becomes combustible.
27. A gas generating system comprising a gas producer adapted to contain a fuel bed of ignited carbonaceous material, a work device, a delivery main connecting said producer with said work device, a pump connected to the delivery main for drawing air and moisture through the fuel bed in said producer to generate gas and for forcing the generated gas through said delivery main under pressure to said work device, a constant speed electric motor driving said pump, an electric circuit for said motor, a switch therein, and means responsive to pressure conditions within said delivery main beyond said pump for intermittently opening and closing said switch.
45. In testimony whereof I hereto affix my signature.

HARRY F. SMITH.

CERTIFICATE OF CORRECTION.

Patent No. 1,772,641.

Granted August 12, 1930, to

HARRY F. SMITH.

It is hereby certified that error appears in the printed specification of the above numbered patent requiring correction as follows: Page 3, line 59, for the word "which" read water; page 4, line 83, for "members" read member; page 11, line 39, claim 1, after the word "holder" strike out the words "for subsequent use" and insert the same to follow "holder" in line 40, of same claim; and that the said Letters Patent should be read with these corrections therein that the same may conform to the record of the case in the Patent Office.

Signed and sealed this 23rd day of September, A. D. 1930.

M. J. Moore,
Acting Commissioner of Patents.
